[57] CLAIM

I claim the ornamental design for the zip around front pocket wallet, as shown and described.

DESCRIPTION

FIG. 1 is a back view of the zip around front pocket wallet showing my new design;

FIG. 2 is a front view thereof;

FIG. 3 is a top view thereof;

FIG. 4 is a bottom view thereof;

FIG. 5 is a right side view thereof;

FIG. 6 is a left side view thereof;

FIG. 7 is a back perspective view of the front pocket wallet with the keychain detached from the wallet; and,

FIG. 8 is a back perspective view of the front pocket wallet with the keychain attached to the wallet.

The broken line showing of paper money in FIGS. 7 and 8 is for illustrative purposes only and forms no part of the claimed design.
